UNITED STATES PATENT OFFICE.

MILTON C. WHITAKER AND WALTER F. RITTMAN, OF NEW YORK, N. Y., ASSIGNEES
TO SYNTHETIC HYDRO-CARBON COMPANY, OF PITTSBURGH, PENNSYLVANIA, A
CORPORATION OF DELAWARE.

APPARATUS FOR MANUFACTURE OF GAS.

1,348,766.

Specification of Letters Patent.

Patented Aug. 3, 1920.

Application filed February 28, 1916. Serial No. 80,956.

To all whom it may concern:

Be it known that we, MILTON C. WHITAKER and WALTER F. RITTMAN, residing at New York, in the county of New York and 5 State of New York, citizens of the United States, have invented or discovered certain new and useful Improvements in Apparatus for Manufacture of Gas, of which improvements the following is a specification.

10 In carrying out of chemical reactions in the industries, it is desirable to obtain a high speed of reaction and an intimate contact of the molecules of the reacting substances. It has been found that many reactions which 15 are now carried out in other than a gaseous phase, can be much more readily obtained when the entire body of the substance or substances to be treated is first transformed into gases and then subjected to the appropriate conditions of temperature, pressure 20 and time, which have been proven suitable for the promotion of the particular reactions desired.

The invention described and claimed herein, relates to apparatus for the carrying out of the method set forth in an application filed April 3, 1914, Serial No. 829,169, said method consisting, broadly stated, in subjecting the material or materials when in 25 a gaseous state for a suitable time to a temperature and pressure suitable for the formation of the desired compound and preventing further reaction injurious to such compound when formed. The invention 30 is hereinafter more fully described and claimed.

In the accompanying drawing, forming a part of this specification, is shown partly in elevation and partly in section a form of 40 apparatus embodying the improvements claimed herein.

In the practice of the invention, the material or materials to be treated are fed into a tube 2 formed of a material capable of withstanding the temperatures and pressures incident to the practice of the carrying out of the method referred to. As the method is continuous, the tube is heated by the external application of heat and as control of the 45 temperature of the tube is desirable under most conditions, and essential in cases, the heating means employed should be adapted to these ends and to the economic conditions

incident to the locality where the plant is located. Hence, although the means shown 55 and described herein have been found suitable and desirable under some conditions and circumstances, the scope of the claims is not limited to the particular form or construction of apparatus employed for heating the tube.

In the apparatus shown, the tube 2 is surrounded by a resistance wire A, suitably insulated from the tube. The tube and its elective heating element are preferably incased in a protective coating of magnesia-asbestos or other suitable refractory material. The ends of the resistance wire A are connected respectively to suitable conductors extending from a suitable source of 65 elective energy, as for example, a direct current generator. A rheostat 10 is included in the circuit of the resistance coil for controlling and regulating the universal supply to the coil in accordance with the heat effects 70 desired. If desired, a pyrometer 11, connected to an appropriate indicator 12 may be employed for ascertaining the temperature within the tube 2.

The material or materials are introduced 80 into the tube 2 at one end thereof by any suitable means. As for example, when it is desired to effect gasification within the tube, the liquid is supplied from a suitable source. When the reaction desired requires 85 a pressure in the tube above atmospheric pressure, the liquid will be subjected to sufficient pressure to cause it to enter the tube. This end may be obtained by arranging the supply reservoir 13 at a suitable height 90 above the inlet into the tube and equalizing the pressure in the upper part of the reservoir with that in the tube, through an equalizing tube 14, communicating at its lower end with the tube and at its upper end with 95 the reservoir at a point above the level of the liquid therein.

In the practice of the method, the material or materials are treated while in a gaseous condition, and hence when fed to the tube 100 in a liquid state, provision is made for "flashing the liquid into gas." Under proper regulation and conditions of the feed, the temperature in the tube will effect the practically instantaneous transformation 105 of the liquid to a gaseous condition, but if

- found desirable to facilitate gasification, a mass of small pieces of refractory material (as small steel balls) may be arranged at the feed end of the tube, thereby providing heating surface, the combined areas of which will be comparatively large. In the construction shown, these balls are supported by a perforated plate 15, which is in turn supported by a rod 16.
- 10 The heating of the body of the tube is sufficient to heat the upper portion thereof, including the perforated plate 15 and the refractory material thereon, to a temperature sufficient to flash into vapor or gas the material coming into contact with the mass of heated refractory material.
- At its lower end, the tube discharges through a condenser 6 into a receptacle 17. This receptacle or segregation chamber 20 which is separate from the heated reaction zone, serves for the collection of liquid condensates and whatever other products may result from the operation of the process. These products may be removed through the 25 valved pipe 18. When a pressure above atmospheric pressure is maintained in the tube, uncondensed gases may be discharged from the receptacle, through the pipe 7. When, however, the desired reaction in the tube requires a pressure below the atmospheric, the receptacle is connected to a vacuum pump 8, by which the uncondensed gases are drawn from the receptacle and fed into a suitable container.
- 35 It will be readily understood that, when a pressure in excess of atmospheric is required to effect a desired reaction, such pressure can be obtained by the proper relative regulation of material to the feed, and the discharge of 40 the resultants of the reaction from the tube. And further, the duration of the reactions in the gasified material can also be controlled by suitably adjusting the feed to and discharge from the tube.
- 45 The duration of the reaction is thus determined by the rate of movement of the gases through the tube and the length of the reaction zone.
- As pointed out in my application Serial 50 No. 829,169, above referred to, the apparatus has been found particularly useful in the treatment of hydrocarbon oils, but it is adapted for use with other materials in which reactions are to be effected in the gaseous phase.
- We claim herein as our invention:—
1. In an apparatus for continuous treatment of materials in the gaseous state, the combination of (1) means for effecting the 60 substantially instantaneous gasification of the materials being treated, (2) a substantially upright reaction chamber connected to said gasifying means and having an unobstructed body portion and means for heating said reaction chamber, (3) a segregating chamber in open communication with the bottom of said reaction chamber, (4) means for controlling the pressure within the reaction chamber.
2. In an apparatus for continuous treatment of materials in the gaseous state, the combination of (1) means for effecting the gasification of the materials being treated, (2) a substantially upright reaction chamber connected to said gasifying means and having an unobstructed body portion and means for heating said reaction chamber, (3) a segregating chamber in open communication with the bottom of said reaction chamber, (4) means for controlling the pressure within the reaction chamber.
- 70 3. In an apparatus for treating materials in a gaseous phase, the combination of means for feeding the material to be treated, a plurality of small spaced surfaces, arranged 85 in the line of the flow of the material, means for heating the objects forming the surfaces, to a temperature above the gasifying temperature of such material and an unobstructed chamber for receiving the gas and means 90 for heating the walls of such chamber.
4. In an apparatus for treating materials in the gaseous state, the combination of a substantially upright chamber, means for heating the chamber, means for introducing 95 material into the upper portion of the chamber, said chamber having a substantially unobstructed body portion, and means within said chamber and above the body portion for gasifying the said material.
5. In an apparatus for treating materials in the gaseous state, the combination of a substantially upright chamber, means for introducing material into the upper portion of the chamber, said chamber having a substantially unobstructed body portion, and means within 100 said chamber and above the body portion for gasifying the said material, said gasifying means comprising pieces of refractory 105 material.
6. In an apparatus for treating materials in the gaseous state, the combination of a substantially upright chamber, means for heating the chamber, means for introducing 110 material into the upper portion of the chamber, said chamber having a substantially unobstructed body portion, and a mass of refractory material arranged across said chamber above the body portion.
- 115 7. In an apparatus for treating materials in the gaseous state, the combination of a substantially upright chamber, means for heating the chamber, means for introducing material into the upper portion of the chamber, said chamber having a substantially unobstructed body portion, and a mass of refractory material supported on a perforated plate arranged above said body portion.
- 120 8. In an apparatus for treating materials 130

- in the gaseous state, the combination of a substantially upright chamber, means for heating the chamber, means for introducing material into the upper portion of the chamber, 5 said chamber having a substantially unobstructed body portion, means within said chamber and above the body portion for gasifying said material, means for controlling the pressure within said chamber, and means for controlling the feed of material 10 to said chamber.
9. In an apparatus for treating materials in the gaseous state, the combination of a substantially upright chamber, means for heating the chamber, means for introducing material into the upper portion of the chamber, 15
- 20

ber, said chamber having a substantially unobstructed body portion, means within said chamber and above the body portion for gasifying said material, means for controlling the pressure within said chamber, and means for controlling the feed of material 15 to said chamber.

In testimony whereof we have hereunto set our hands.

MILTON C. WHITAKER.
WALTER F. RITTMAN.
